UNITED STATES PATENT OFFICE.

EDWIN FAY HOPKINS, OF CLEVELAND, OHIO, ASSIGNOR TO CHARLES A. STEDMAN, OF SAME PLACE.

CARPET-TACK.

SPECIFICATION forming part of Letters Patent No. 507,541, dated October 31, 1893.

Application filed June 7, 1893. Serial No. 476,823. (No model.)

To all whom it may concern:

Be it known that I, EDWIN FAY HOPKINS, a citizen of the United States, residing at Cleveland, in the county of Cuyahoga and State of Ohio, have invented certain new and useful Improvements in Carpet-Tacks; and I do declare the following to be a full, clear, and exact description of the invention, such as will enable others skilled in the art to which it applies to make and use the same, reference being had to the accompanying drawings, and to the letters of reference marked thereon, which form a part of this specification.

The special object of the invention is to make a tack for fastening down carpets after they have been stretched into the exact position desired, the same being constructed in such a form as will admit of their ready removal from the floor and of their repeated use.

Figure 1 of the drawings is a perspective view of my carpet tack; Fig. 2 a vertical section, showing it applied to the carpet and floor. Fig. 3 is a detail view of a modification.

In the drawings, A represents my carpet-tack which has a flat top a with diametrically

opposite ears a' a' bent downwardly and curved under the said top, a pointed shank a^2 and an enlarged neck a^3 flat on the under side. The ears a' a' are arranged, when the tack is being driven through the carpet into the floor, so that the prongs of the lifter can be readily inserted therein, and the ends are curved under so that the metallic head will not be liable to mash down at the edges and thus defeat the object of the invention.

Instead of the neck a^3 shown in Figs. 1 and 2 of the drawings, I may use a fixed collar as shown in Fig. 3.

Having thus described all that is necessary to a full understanding of my invention, what I claim as new, and desire to protect by Letters Patent, is—

The carpet-tack A having the flat top a with ears a' a' diametrically opposite and curved under the top, the pointed shank a^2 and the enlarged neck a^3 as shown and described.

In testimony whereof I affix my signature in presence of two witnesses.

EDWIN FAY HOPKINS.
